Primary Examiner — Andrew Kerr*Assistant Examiner* — Courtney J Clark-Rasheed(74) *Attorney, Agent, or Firm* — Janeway Patent Law PLLC; John M. Janeway(57) **CLAIM**

The ornamental design for a lid for a cup, as shown and described.

DESCRIPTION

FIG. 1 is a perspective view of a lid for a cup showing my new design;

FIG. 2 is a rear elevation view thereof;

FIG. 3 is a front elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings depict portions of the lid for cup that form no part of the claimed design.
